PAPER FEEDING MECHANISM

Application filed November 30, 1931. Serial No. 577,973.

The object of this invention is to provide a simple and effective mechanism for the accurate and certain feeding of paper sheets. The invention is useful in conjunction with printing machinery, folding machinery, etcetera. It acts on a manually advanced pile of superimposed sheets to feed the bottom sheet and at the same time accurately guide it, whereby a perfect fold or perfect registration may be obtained in the subsequently acting mechanism.

To the above end, I provide a supporting bar extending across the front of the mechanism to which the paper is to be fed; and I mount on this cross bar, adjacent its ends, two adjustably positioned guides engaging the under face and the edges of the bottom sheet, and I secure to the cross bar, between these guides, a frame carrying a feed roll adapted to coact with an under roll and carrying also mechanism for bending the lowermost sheet slightly about the ends of such under roll to prevent slippage and insure an accurate feed. My invention is more fully hereinabove described in connection with the drawings, and its essential and novel features are summarized in the claims.

The drawings illustrate a preferred embodiment of my invention. Fig. 1 is a plan partly broken away of the feeding mechanism and a roller of the machine to which the paper is to be fed; Fig. 2 is a sectional side elevation of the same, as indicated by the line 2-2 on Fig. 1; Fig. 3 is a perspective of a portion of one of the paper guides clamped to the supporting bar; Fig. 4 is a central longitudinal section to the feeding rollers, as indicated by the line 4-4 on Fig. 1; Fig. 5 is a transverse section in a plane indicated by the line 5-5 on Fig. 4, showing the feeding roller arrangement in end elevation.

As indicated in Figs. 1 and 2, A and A' designate a pair of rollers of a folding machine, or printing machine, or some other mechanism to which the paper is fed. These rollers are mounted in a suitable frame indicated at B. To enable my mechanism to be accurately positioned with reference to the rollers, I provide first a transverse support

ing bar 10 which is shown as secured by bolts 11 to suitable arms b formed on the frame B. This bar 10 is rectangular in cross section, except that the front top edge is chamfered, as indicated at 12, for a purpose 55 hereinafter described.

Secured to the front side of the frame B, as by a suitable bracket 15, is a plate 16 on which my feeding mechanism may rest, and extending through this plate is the under feed roller 40, hereinafter described, the shaft 41 of which may be journaled in the bracket 15, or be otherwise mounted as desired.

To properly guide the pile of sheets, and particularly the bottom sheet which is the one engaged and fed, I provide specially formed guide members which rest on the plate 16 but are adjustably mounted on the cross bar 10 and held in position thereby. Each guide member consists of a bar 20 having a vertical inner face 21 and a flat plate 22 secured (as by screws 23, Fig. 5) to the underside of the bar 20. The plate 22 has a smooth top and snugly joins the bottom of 75 the bar 20 so that there is no crack between them, and the bottom sheet of paper designated C in Fig. 5 rests on the plate 22 and is guided, at its edge, by the vertical wall 21.

Each bar 20 is formed at its rear edge with a lip 25 adapted to lie beneath the cross bar 10 and with a rear flange 26 adapted to engage the back edge of that cross bar, as shown in Fig. 3. The guide bar is also provided with a vertically extending transverse web 27 which stands some distance in front of the cross bar 10 and terminates in a rearwardly inclined web 28, as shown in Fig. 4. Extending through the diagonal web 28 is a clamping screw 29 lying at an angle of 80 approximately 45° and provided with a knurled head. When this screw is turned in, its inner edge engages the bevel 12 on the bar 10, and thus forces the rear end of the guide bar upwardly and forwardly, causing its web 25 to bear snugly against the under face of the bar, and its web 26 to bear snugly against the rear edge of the bar. At the same time, the body of the guide bears down 95 on the plate 16, the direction of the chamfer 100

12 and the screw 29 being selected to effect this result.

The construction of the guide bar just described enables the sheets to be very accurately positioned. By merely loosening the screws 29, the bars may be shifted laterally, according to the width of the paper to be fed, so that the vertical surfaces 21 may be brought close to the edges of the paper sheets; while the bottom plates 22 prevent even the thinnest sheet working under the guide bar.

The same cross bar 10 which carries the guide bars, carries also my feeding unit. This comprises a frame bracket 30 secured by bolts 31 to the cross bar 10; an extension bracket 32 secured by screws 33 to the under side of the main bracket 30; a swinging housing 35 pivoted to the bracket 32 by means of a rod 36, and a roller 37 carried by the housing. A spring 38, embracing the rod 36, tends to lift the housing and roller 37; and a screw 39, mounted in the frame bracket 30 and pushing downwardly against the top of the housing 35, limits the upward movement thereof. In this manner, the roll 37 may be accurately positioned.

Beneath the roll 37 is the coacting feed roll 40 heretofore mentioned. On one end 30 of the shaft 41 of this roll is shown a sprocket wheel 44 connected by a sprocket chain 45 with a sprocket wheel 46 on the shaft of the roller A' of the machine to be served. The roller 40 is driven at the same peripheral speed as the rollers A and A'. This may be readily effected by making the roller 40 of the same diameter as the roller A', and making the two sprocket wheels 44 and 46 of one diameter, as illustrated in the drawings.

The upper feed roller 37 is positioned with reference to the roller 40 by turning the screw 39 to increase or decrease the pass between the rollers, according to the thickness of the paper to be fed. The screw 39, acting against a mid-region of the housing supported by the spring, enables the roller 37 to be positioned evenly and accurately by simply operating the single screw 39.

To insure the sheet being grasped by the rollers 37 and 40, I provide a pair of fingers 50, pivotally mounted in the feeding unit and adapted to shove downward on the paper slightly beyond the ends of the roller 40 to bend the paper about the roller, as shown at c in Fig. 5. I have found that this insures the engagement of the paper and causes reliable feeding.

As shown in the drawings, the two fingers 60 50 are flat bars extending edgewise and mounted on the cross bar 36 on which is mounted the roller housing 35. The fingers are connected near their upper ends by a cross bar 53 to which is secured, centrally, 65 an ear 54 in which is anchored a tension

spring 55. The other end of this spring is shown as anchored to a plate 56 formed on a nut 57 on the screw 39. A screw 59 passes through the bar 53 and abuts the edge of the frame plate 30, and thus limits the downward movement of the lower end of the fingers 50. As shown, the screw 59 also serves the purpose of longitudinally positioning the ear 54 which is a piece of sheet metal embracing the rod 53.

The fingers 50 extend diagonally downward and rearward and are gradually curved at their lower edges, as shown at 51. Accordingly, the space between these lower edges and the plane defining the top of the guide wings 22 approximates, in shape, the form of the edge of a fanned-out pile of sheets; and therefore the curved edges 51 of the fingers serve to properly hold back the sheets of paper above the bottom sheet, as well as to press the bottom sheet about the lower feed roller 40 to an extent readily determined by the screw 59.

For certain grades or weights of paper, the fingers 50 may be unnecessary, and they can then be rendered idle by turning in the screw 59 approximately to its limit; but for thin paper, and particularly glazed paper, I find that it is very desirable to have the fingers acting lightly and to a slight extent against the sheets of paper, and particularly the bottom sheet adjacent the end of the lower feed roll.

My entire mechanism is simple in construction, and may be readily attached to machines to be fed. It is easily adjustable for different size sheets and different thicknesses and grades of paper, and to give the right amount of pressure on the sheet to bend it just sufficiently to insure its proper feeding. The sheet, while being fed, is effectively supported by the guide wings 22 and guided by the vertical surfaces of the bars. However, the mere loosening of the guide bar screws enables the guides to be positioned as desired for different widths of paper.

I claim:

1. A paper feeding mechanism, comprising a transverse supporting bar, a pair of guide bars adjustably clamped to the supporting bar, and a centrally located rotary feeding unit carried by the supporting bar between the guide bars.

2. In a device of the character described, the combination of a supporting bar adapted to be secured across the front of a machine to be fed, a feeding unit comprising a bracket carried by the supporting bar and a roller mounted in a member pivoted to said bracket, and adjustable with reference to a coacting lower roller, and opposite side guides for the sheet of paper to be fed by the rollers, each guide comprising a bar adjustably clamped to said supporting bar.

3. In a paper feeding mechanism, the combination of a centrally located feeding unit comprising a pair of rollers, one above the other, and a pair of adjustable guides on opposite sides of the feeding unit, each guide comprising a bar having a vertical surface and a plate secured to the under side of the bar and projecting inwardly and adapted to support the paper, and means for adjustably 10 clamping said guides parallel to each other on opposite sides of the feeding unit.

4. A paper feeding mechanism, comprising a frame bar, a pair of parallel paper guides adjustably carried thereby, a bracket 15 carried by the bar between the guides, a housing pivotally mounted on the bracket, a roller carried by the housing, a spring tending to elevate the roller, a screw adapted to lower the roller against the action of the 20 spring, and an under roller with which the roller first mentioned may coact.

5. In a paper feeding mechanism, the combination of a transverse supporting bar, a pair of paper guides, each comprising a bar 25 having a vertical surface and a plate closely secured to the under side of such bar and projecting inwardly and adapted to support the paper, a paper feeding mechanism located between the guides and comprising a pair 30 of coacting feed rolls and means adapted to bend the paper about the ends of one of such rolls.

6. The combination of a cross bar, a bracket carried thereby, a feed roller and 35 a pair of fingers at the opposite ends thereof all carried by the bracket, another roll with which the roll mentioned coacts, said fingers being adapted to bend the paper about the ends of one of such rolls.

40 7. A paper feeding mechanism, comprising a pair of coacting feed rollers one above the other, a pair of fingers at the opposite ends of said rolls, and spring means press- ing the fingers downwardly to bend the pa- 45 per about the ends of the under roll.

8. In a paper feeding mechanism, the combination of a pair of coacting rolls, a pair of 50 pivoted fingers having paper engaging sur- faces beyond but adjacent the opposite ends of one of the rolls, and adapted to bend the paper about such roll.

9. In a paper feeding mechanism, the combination of a pair of coacting rolls, a 55 pair of fingers respectively adjacent oppo- site ends of one of the rolls, and spring means acting on the fingers to cause them to bear lightly on the paper and bend it about one of the rolls.

60 10. In a paper feeding mechanism, the combination with a feed roll, of a surmount- ing roll adjustable toward and from the feed roll mentioned, a pair of diagonally located 65 fingers at the opposite ends of the two rolls, said fingers being pivotally carried and

spring pressed to intercept the path of the paper between the rolls.

11. In a mechanism of the class described, the combination of a supporting bar, a bracket carried thereby, a roller pivotally mounted on the bracket, another roller with which the roller first mentioned coacts, a pair of fingers pivotally mounted on the bracket and lying at the ends of the two rollers and adapted to extend across the path 70 of the paper to them, and a spring connected to the fingers for forcing their lower ends toward the paper. 75

12. In a device of the character described, the combination of a frame bracket, a rod 80 carried thereby, a housing pivotally mounted on the rod, a roller carried by the housing, a spring tending to elevate the housing, a screw mounted in the bracket and tending to lower the housing, a pair of fingers 85 mounted on the rod, a spring tending to swing the fingers to lower their ends, and a screw for limiting such downward movement of the fingers.

13. The combination with means for sup- 90 porting paper in a plane, of a feeding mech- anism, comprising a pair of coacting feed rolls, and means to bend an intermediate region of a sheet of paper slightly about the ends of one of said rolls while preserving the 95 marginal portions of the sheet in its original plane.

14. In a paper feeding mechanism, the combination of a paper feed table, a feed roll projecting above the plane of the table, 100 and means adapted to bend about the ends of the roll a sheet of paper lying on the table.

15. A paper feed mechanism, comprising 105 a feed table, a feed roll projecting upwardly through an opening in the table, a surmount- ing feed roll, and means to bend downwardly at the ends of the lower roll an intermediate region of a sheet of paper resting on the table and passing between the rolls. 110

16. A paper feeding mechanism, comprising 115 a pair of coacting feed rolls, a pair of downwardly extending fingers respectively at opposite ends of the rolls, and means adapted to guide paper beneath the fingers to bend it about one of the rolls without permanently deforming it.

17. The combination of a paper feed table, a pair of coacting feed rolls, one located 120 above the table and the other below the table by projecting through an opening in the table, a pair of fingers at the opposite ends of the upper roll depending across the upper edge of the lower roll and adapted to bend paper passing beneath the fingers down- 125 wardly toward the table.

18. A paper feeding mechanism, comprising 130 a pair of coacting feed rolls, a pair of downwardly extending movable fingers re- spectively at opposite ends of the rolls,

means adapted to guide paper beneath the fingers, and spring means acting on the fingers to cause them to bend the sheet slightly about the ends of one of the rolls.

- 5 19. In a paper feeding mechanism, the combination of a pair of coacting rolls, one above the other, a pair of pivoted fingers farther apart than the length of the rolls and respectively adjacent the opposite ends 10 of the upper roll, each finger having its lower front edge curved downwardly and rearwardly and adapted to extend beyond a pro-

longation of the cylindrical surface of the lower roll.

20. In a paper feeding mechanism, the combination of a feed roll, a surmounting roll, a pair of diagonally located fingers adjacent the opposite ends of the two rolls, said fingers being farther apart than the length of the rolls and being pivotally carried and inclining away from the paper supply to intercept the path of the paper between the rolls.
